[57] CLAIM

The ornamental design for projection television receiver, as shown and described.

DESCRIPTION

FIG. 1 is a front, top and right side perspective view of a projection television receiver showing our new design;

FIG. 2 is a view similar to FIG. 1 with a cover pivoted to open position;

FIG. 3 is a front elevational view of the receiver in the condition of FIG. 1;

FIG. 4 is a right side elevational view thereof;

FIG. 5 is a rear elevational view;

FIG. 6 is a left side elevational view of the receiver in the condition of FIG. 2;

FIG. 7 is a top plan view of the receiver in the condition in FIG. 1;

FIG. 8 is a bottom plan view thereof; and

FIG. 9 is a view similar to FIG. 7 of the receiver in the condition of FIG. 2.
